CLAIM

The ornamental design for a portable motion detector, as shown and described.

DESCRIPTION

FIG. 1 is a side perspective view of a portable motion detector showing my new design in an extended position, with the other side views being identical;

FIG. 2 is a side perspective view thereof in a retracted position, with the other side views being identical;

FIG. 3 is a top thereof; and,

FIG. 4 is a bottom view thereof.

FIG - 1

FIG - 4

FIG - 3

FIG - 2

UNITED STATES PATENT AND TRADEMARK OFFICE
CERTIFICATE OF CORRECTION

PATENT NO. : D 351,806
DATED : October 25, 1994
INVENTOR(S) : Bert S. Bedrosian

It is certified that error appears in the above-identified patent and that said Letters Patent is hereby corrected as shown below:

On the title page:

Item [73]   Assignee: Replace "luard-Tech" with
--Guard-Tech--.

Signed and Sealed this
Fourth Day of April, 1995
